UNITED STATES PATENT OFFICE

162,680

OZONE-PRODUCING AND GERM-KILLING APPARATUS CABINET

Irving Naxon, Chicago, Ill.

Application July 29, 1950, Serial No. 11,488

Term of patent 14 years

(Cl. D26—5)

To all whom it may concern:

Be it known that I, Irving Naxon, a citizen of the United States, residing at 3001 W. Jarvis Avenue, Chicago 45, State of Illinois, have invented a new, original, and ornamental Design for Ozone-Producing and Germ-Killing Apparatus Cabinet, of which the following is a specification, reference being had to the accompanying drawing, forming a part hereof.

Fig. 1 is a top plan view of an ozone-producing and germ-killing apparatus cabinet showing my new design;

Fig. 2 is a front elevational view; and

Fig. 3 is a side elevational view thereof.

I claim:

The ornamental design for an ozone-producing and germ-killing apparatus cabinet, as shown.
IRVING NAXON.
